CHILD'S PLAY CHEST

Merrill L. Hassenfeld, Providence, R.I., assignor to Hasbro Industries, Inc., Pawtucket, R.I.

Filed Mar. 16, 1970, Ser. No. 21,924

Term of patent 14 years

Int. Cl. D21—02

U.S. Cl. D34—15

FIG. 1

FIG. 2

FIG. 3

FIG. 4

FIG. 5

FIG. 6

FIG. 1 is a front elevational view of a child's play chest showing my new design;

FIG. 2 is a side elevational view thereof;

FIG. 3 is a rear elevational view thereof;

FIG. 4 is an elevational view of the other side thereof;

FIG. 5 is a top plan view thereof; and

FIG. 6 is a bottom plan view thereof.

I claim:

The ornamental design for a child's play chest, substantially as shown.
